UNITED STATES PATENT OFFICE.

CHARLES H. HOLT, OF PHILADELPHIA, PENNSYLVANIA.

GRATE FOR BOILER-FURNACES.

SPECIFICATION forming part of Letters Patent No. 312,472, dated February 17, 1885.

Application filed November 17, 1882. (No model.)

To all whom it may concern:

Be it known that I, CHARLES H. HOLT, a subject of the Queen of Great Britain, residing in the city and county of Philadelphia, State of Pennsylvania, have invented a new and useful Improvement in Grates for Boiler-Furnaces, &c., which improvement is fully set forth in the following specification and accompanying drawings, in which—

10 Figure 1 is a front view, partly sectional, of the grate embodying my invention. Fig. 2 is a rear view thereof. Fig. 3 is a longitudinal vertical section thereof.

Similar letters of reference indicate corresponding parts in the several figures.

15 My invention relates to improvements in an endless grate of the order known as "traveling," the direction of motion whereof is such that the fuel is systematically admitted at the 20 front of the furnace and carried toward the rear thereof, the draft-opening of the furnace being at the rear, so that the draft-entrance is opposite to the feed-opening, whereby the furnace is uniformly supplied and the fire equably 25 maintained throughout the length of the grate.

It also consists of other details of construction, as will be hereinafter set forth.

Referring to the drawings, A represents a series or number of grate-bars, a, jointed one 30 to another, forming an endless grate, which is supported at opposite ends on rollers or drums B, of polygonal form, and the part which is above and intermediate of its ends on stretchers C, the bearing of said rollers and the 35 stretchers being sustained on masonry, brick-work, or other suitable supports, the boiler or other object to be heated being likewise properly sustained or supported.

In the front wall of the masonry, just above 40 the upper part of the grate, is a throat, D, which forms a communication with the combustion-chamber of the furnace and permits the passage of the grate thereto. The grate is extended beyond the front wall of the masonry, so as to form a hearth, E, the sides 45 whereof have guards F, for preventing lateral displacement of the fuel placed on the hearth, said guards being secured to the masonry, but may be otherwise properly held in position.

Guided in the front wall of the masonry is 50 a sliding gate or door, G, which is adapted to move to and from the top of the grate, so as to cover and uncover the throat D, said door having fitted to it vertical screw rods or bolts H, which are geared together, whereby by the 55 operation of a crank or hand-wheel, b, attached to one of the shafts of the gearing, said rods may be rotated, and the door G thereby raised and lowered.

To the axis or bearing of the rear roller, B, 60 is attached a worm-wheel, J, with which engages a worm, K, the shaft K' whereof is properly mounted on the masonry or support of the grate, and carries a ratchet, L, the operating-pawl M whereof is hung on an elbow-lever or angular arm, N, which is fitted loosely on the shaft K', and receives motion from a shaft, P, through the medium of an eccentric, Q, on said shaft, and a connecting-rod, R, said shaft having power imparted to it in any 65 suitable manner, and the lever N being slotted, as at d, to receive the attaching-bolt e of the rod R, whereby the throw of the pawl M may be adjusted.

It is evident that when the grate is employed 70 in the furnace of a steam-boiler the shaft P may be operated by steam-power through the medium of pulleys, belts, or other suitable devices connected with the engine or machinery driven thereby.

80 S represents a door of the furnace at the rear thereof, above the grate, the same having its frame secured to the masonry; and to said frame, or another suitable support adjacent thereto, is hinged a chute or scraper, T, which 85 overhangs the top of the grate, and has one end in contact therewith, said end projecting toward the front of the furnace.

The operation is as follows: The fuel, which 90 may be bituminous or anthracite coal, shavings, refuse, &c., is placed on the projecting front of the grate or hearth, the door G raised, and power communicated to the arm N, so as to raise and lower the same, the effect whereof is to cause an intermittent motion of the shaft 95 K' through the medium of the pawl and ratchet M L. This operates the worm and worm-wheel K J or other suitable gearing.

which may be employed in lieu thereof, and rotates the drum connected with said worm-wheel, whereby the grate is caused to move or travel in a gentle and uniform manner, the direction of motion being from the front to the rear of the furnace. The fuel is carried by the grate through the throat D, the stream or quantity being regulated by the door G, which, as has been stated, is adapted to be raised and lowered, and thus adjust the extent of opening and closing of the throat. The draft of the furnace is from the rear thereof, and after the fire is fairly started and the fuel begins to be consumed a fresh supply of fuel is carried into the furnace by the traveling grate in a steady manner and to uniform extent, and the bed of fuel is constantly fed with fresh fuel, whereby an equable fire is maintained throughout the length of the grate or furnace. The ashes as formed fall or are poked through the grate-bars into the pit below, and such as reach the chute and scraper T are cleared by the latter and ascend the same to or toward the rear door, S, where they may be removed. The grate-bars as cleared or scraped pass around the rear roller, and after passing around the front roller return to the hearth and again serve to convey fresh fuel into the furnace. As the greatest heat is at the front of the furnace the fresh fuel is quickly ignited, and the fire is not checked or cooled down by the admission of cold air during the process of supplying fresh fuel, as by hand firing. It will also be seen that on account of the heat or flames passing over the fresh automatically supplied fuel it will ignite and burn from the top, and thereby instantly mix with and

consume the smoke and gases at the point of emission from bituminous or other gaseous or smoky fuel, and the evaporative power in the case of the boiler for the coal burned must necessarily be greater than if the gases had escaped past the boiler unconsumed.

The door S also permits access to the furnace at the rear thereof and may be employed as a damper for the fire.

Owing to the exposure of the door G to the flames or products of combustion generally, said door is made hollow, or of box form, and lined with fire-brick or other suitable material, so that the latter is presented toward the throat D, whereby the door is protected and burning of the mass of fresh fuel on the hearth prevented.

Having thus described my invention, what I claim as new, and desire to secure by Letters Patent, is—

1. An endless traveling grate, in combination with the inclined guide and scraper, a door above said scraper, and a draft-entrance below said grate, the scraper, door, and draft-entrance being at the rear of the traveling grate, substantially as and for the purpose set forth.

2. An endless traveling grate having one end extended in front of the furnace, forming a hearth, a supply-throat in front, a draft-entrance in the rear, and an inclined guide and scraper overhanging the rear end of said grate, substantially as and for the purpose set forth.

CHARLES H. HOLT.
